UNITED STATES PATENT OFFICE.

ELBERT BIRD HARRAL, OF NEW-ORLEANS, LOUISIANA.

RAILWAY PACKAGE-TRANSFERRING DEVICE.

1,153,071.

Specification of Letters Patent.

Patented Sept. 7, 1915.

Application filed April 12, 1913, Serial No. 760,727. Renewed May 12, 1915. Serial No. 27,666.

To all whom it may concern: Be it known that I, ELBERT B. HARRAL, a citizen of the United States, and a resident of New Orleans, in the parish of Orleans and State of Louisiana, have made certain new and useful Improvements in Railway Package-Transferring Devices, of which the following is a specification:

My invention relates to railway package transferring devices, such for instance as may be employed in transferring mail bags from a mail car to a station, or from the station to the mail car, the more particular purpose of my invention being to provide an improved mechanism whereby the delivery of the package is accomplished with a minimum of risk, and in which the momentum or inertia of the package is gradually overcome by aid of an inclined surface, or by causing the package to slide upon a surface properly curved to check the relative motion of the package.

Reference is made to the accompanying drawing forming a part of this specification, and in which like letters indicate like parts.

Figure 1 is a plan view showing my apparatus as used for transferring a mail bag from a car to a station. Fig. 2 is a side elevation showing the station and a portion of my mechanism associated therewith. Fig. 3 is a detail showing in cross section one of the fingers used for handling the package. Fig. 4 is an end elevation of the mechanism shown in Fig. 1. Fig. 5 is a plan view showing my device as used for delivering mail from the station to the moving car.

The station is shown at 6, and at 7, 7^a, are horizontal arms which are supported upon posts 8, 8^a. Braces 9 are employed for strengthening these posts. A chute is shown at 10 and is provided with side boards 11 terminating at their ends in flanges 12, the latter being bent slightly outward or away from each other. A number of fingers 13 made of metallic rods are connected with the chute and extend therefrom. These fingers are each provided with a rib 14, and with an upturned or hooked end 15. The chute 10 is provided with a slanting portion 16, that is, a portion forming an inclined plane surface. The chute is further provided with a portion 17 which is curved in a substantially horizontal plane. A railway car is shown at 18 and

rests upon a track 19. The car carries an arm 20, this arm being strengthened by braces 21. The arm is further provided with fingers 22, each of arcuate form. A package 23 such as a mail bag is rested upon the fingers 22, and as the car passes the station and moves to the left according to Fig. 1, the package is engaged by the fingers 13. The package, owing to its momentum, glides upwardly on the inclined surface of the chute, and upon reaching the level of the highest portion of the chute, glides in a circular path, as will be understood from Fig. 1. The momentum of the package is thus gradually overcome without injury to the contents of the package. The manner in which the package is removed from the fingers 13 and transferred to the chute is indicated in Fig. 2, the fingers 13 being shown by full and dotted lines in this figure for the purpose of representing its longitudinal motion relatively to the chute.

For the purpose of transferring the package from the station to the car, I employ the arrangement shown in Fig. 5 which differs from that shown in Figs. 1, 2 and 4 in that according to Fig. 5 the chute is carried by the car and the mechanism for releasing the package is located at the station. The chute is shown at 24 and is preferably built a little more compactly than the chute 10, but is otherwise similar to the latter.

The chute 24 is provided with side boards 90 11, having flanges 12. The chute is also provided with fingers 25 having upturned ends 15, these fingers, except for their mounting, being similar to the fingers 13 shown in other figures. The station is shown at 26, and adjacent to the station is a horizontally disposed arm 27. This arm as to structure is similar to the arm 20, and it is similarly provided with braces 21 and fingers 22. A car is shown at 28, the chute 100 24 being mounted upon and carried by it.

With the mechanism shown in Fig. 5, the package is placed upon the fingers 22 at the station 26, and as the car 28 passes this station the fingers 25 run beneath and between the fingers 22, thus lifting the package. The inertia of the package causes the package to glide upwardly upon the chute and also to describe a curve so that the package thus gradually acquires the general 110 travel motion of the car 28.

It will thus be seen that my device com-

prises two package handling members, one located at a station and the other carried by a movable car, one of the package handling members being for the purpose of discharging the package and the other being in the form of a chute for receiving the package, the chute having a portion or surface serving as an inclined plane upon which the package may glide obliquely upward for the purpose of overcoming the momentum or inertia, as the case may be, of the package, as the latter is delivered to the member for receiving it.

I do not limit myself to the precise construction shown, the scope of my invention being commensurate with my claims.

I claim:

1. A railway package transferring device comprising a group of fingers for holding and releasing a package, and a chute for receiving said package, said chute being provided with fingers having upturned ends, said chute being further provided with a portion inclined obliquely in relation to the horizon for the purpose of causing the package to glide obliquely upward, said chute being further provided with a substantially horizontally disposed curved portion, said curved portion and said obliquely inclined portion being for the purpose of arresting the momentum or inertia of the package as delivered to said chute.

2. A device of the character described comprising two package handling members, one located at a station and the other carried by a car, one of said members being

provided with fingers for the purpose of supporting and easily discharging the package, the other of said members having the form of a chute provided with side walls 40 and with flanges outwardly extended at the ends of said walls, said chute being further provided with fingers extending from the end of the chute and spaced apart, said chute being further provided with a substantially horizontal portion curved in a horizontal plane, said chute being further provided with a portion between the curved portion and said fingers, said last mentioned portion being inclined obliquely in relation 50 to said horizontally disposed portion.

3. A railway package transferring device comprising two package handling members, one located at a station and the other carried by a car, one of said members being 55 for the purpose of discharging the package and the other having the form of a chute for receiving said package, said chute being provided with a substantially horizontal portion and with a portion inclined obliquely downward from said horizontal portion, the inclined portion being provided with fingers extending from it and spaced apart, said fingers virtually constituting a continuation of the inclined portion, each 60 of said fingers being provided with a rib integral with it for the purpose of strengthening it.

ELBERT BIRD HARRAL.
